drews, and Joseph S. Cipolla

Application January 14, 1950, Serial No. 138,638

12 Claims. (Cl. 132—40)

1

This invention relates to an apparatus for permanently waving hair on the human head. The present invention is a continuation-in-part of my copending application for "Method and Means for Hair Waving," Serial No. 14,725, filed March 13, 1948, now United States Letters Patent No. 2,508,374, dated May 23, 1950, and is a division of my copending application for "Apparatus for Permanently Waving Hair," Serial No. 67,348, filed December 27, 1948, now United States Letters Patent No. 2,508,375, dated May 23, 1950.

It is an object of my invention to provide an apparatus of the character described which is particularly useful for home waving and through whose use a comparatively unskilled person can give either herself or someone else a permanent wave of professional appearance.

It is another object of my invention to provide an apparatus of the character described which is of an inherently simple construction and is extremely easy to use.

It is another object of my invention to provide an apparatus of the character described through whose use the hair is permanently waved in ringlet form, whereby not only is the first setting operation eliminated, but the basic wave is of the proper shape and character for subsequent setting operations, this being in contrast to the spiral and Croquignole waves heretofore imparted which had to be reset after completion of waving.

It is another object of my invention to provide an apparatus of the character described through whose use the hair tresses are kept wound until a later stage of operations than ever reached before in permanent waving, whereby the permanency of the wave is enhanced.

It is another object of my invention to provide an apparatus of the character described which is specially adapted to be employed in conjunction with "cold wave" processes.

It is another object of my invention to provide an apparatus of the character described in which curls can be wound in any desired direction, i. e. clockwise or counterclockwise.

It is an additional object of my invention to provide an apparatus of the character described through whose use curls may be wound with ease right up to the scalp.

Other objects of my invention will in part be obvious and in part will be pointed out herein-after.

My invention accordingly consists in the features of construction, combinations of elements and arrangements of parts which will be exemplified in the constructions hereinafter described 55

and illustrated, and of which the scope of application will be indicated in the appended claims.

In the accompanying drawings in which is shown one of the various possible embodiments 5 of my invention.

Fig. 1 is a perspective view of a waving unit embodying my invention;

Fig. 2 is an enlarged sectional view taken substantially along the line 2—2 of Fig. 1;

10 Figs. 3 through 6 are perspective views of the unit at successive stages of a waving operation; and

Fig. 7 is a perspective view of a form of element designed for use in conjunction with the waving unit of Fig. 1.

Referring now in detail to the drawings, and more particularly to Figs. 1 through 7, the reference numeral 50 denotes a waving unit embodying my invention, said unit comprising a quill 52 of relatively rigid material, for example, a stiff plastic which is inert to the chemicals used in the hair waving process. The unit also includes a disc 54 of a flexible resilient material, i. e. an elastomer as rubber or any one of the well known elastomeric plastics, e. g. a polyethylene plastic.

The quill 52 is hollow and is provided with a single flange, to wit, a flange 56 at the end of the quill which engages the disc. This flange is designed to prevent the quill from accidentally becoming disengaged from the disc.

30 The disc has a central opening 58 with a diameter equal to or slightly smaller than the outer diameter of the quill adjacent the flange 56, whereby, when the quill is disposed in said opening, it will be frictionally engaged by the side walls thereof and thus be detained in any given angular position with respect to the disc.

In order to avoid working to too close tolerances with the internal diameter of the opening 40 58 and outer diameter of the quill 52, I provide said disc with a series of through slots 60 which may be of arcuate shape and are disposed a short distance away from the opening. More than one of these slots may be provided, as indicated, and the same are arranged concentrically about the center of said opening 58. Said slots permit the walls of said opening to give slightly so that the actual size of the opening is not critical. With a construction such as just indicated the disc may be made by molding with a satisfactory degree of accuracy.

The disc includes a slit 62 extending from adjacent the opening 58 to the periphery of the disc and of a comparatively complex shape. Said 50 slit includes an arcuate section 64 concentric

with and near the opening 58. The arcuate section runs into a radially extending reach 65 which terminates at a portion 66 which is of such shape as to define a tab 68 with a narrow base 70. The slit runs from the tab to the periphery of the disc. The tab thus is in one piece with the part of the disc at one side of the slit 62 and the mating opening for receiving the tab is on the part of the disc at the other side of the slit. Said tab is designed to be snugly fitted into its mating opening, whereby when the tab is disposed in said opening the two parts of the disc on opposite sides of the slit 62 will be detachably engaged and thus be able to hold the base of a tress securely in place.

The portion of the disc on either side, e. g. the tab side, of the slit 62 may be provided with a slight radially extending projection 72 whereby a user of the waving unit easily is able to locate the slit 62 when it cannot easily be seen in a mirror.

Desirably, and for a purpose which will soon be apparent, the outer surface of the quill may taper very slightly from its free end to adjacent the flange 56. This taper is so slight that it hardly can be noticed in Fig. 2. Said taper is such that the outside diameter of the quill adjacent the flange 56 is about equal to the inside diameter of the quill adjacent the free end 74 thereof.

The waving unit 50 is designed to be employed in conjunction with a rubber or rubber-like element 76 which comprises an elongated bar portion 78 and a plug part 80 which is adapted to be snugly fitted into the hollow free end 74 of the quill. The bar portion 78 is approximately equal in length to the diameter of the disc 54.

The waving unit 50 is employed as follows. The hair on a head 82 first is blocked off as indicated in Fig. 3 so as to subdivide the hair into a group of tresses having a desired base configuration. As illustrative herein, the base configuration of the tress is approximately square. However, it may be somewhat elongated and even considerably elongated. Nevertheless, in the preferred form of my invention, wherein the hair is permanently waved in the form of ringlets, I have found that the most satisfactory results are obtained where the base of the tress is not considerably elongated as it would be, for example, in Croquignole waving.

Each tress is wetted with a conventional so-called "cold wave" softening lotion which is combed through the tress to insure even distribution. Many such solutions are well known to the art. Mention is made here, only by way of example, of a typical softening solution, to wit, one principally including a reducing agent such as ammonium thioglycollate. The distal end of the tress then is caught on the quill near its free end 74 as shown in Fig. 3 and the quill and disc rotated together about the axis of the quill toward the base of the tress. Thereupon, the quill and disc are turned through an angle of 90° with respect to an axis transverse to the longitudinal axis of the quill to bring the disc substantially parallel to the scalp as shown in Fig. 4. The disc then is manipulated to spread apart the two portions on opposite sides of the slit 62 and the base of the tress is introduced into the arcuate section 64. Thereafter, the tab 68 is forced back into its mating opening and the disc firmly clasps the base of the tress. Next the quill is rotated a slight additional amount rela-

tive to the disc in the direction of its winding, whereby to wind the tress close to the scalp.

After winding, if desired, the hair can be re-wetted with a softening solution or optionally a softening solution can be applied only after winding. Thereafter individual wound tresses or the entire wound head of hair is covered to retain the body heat and the wound tress is left for a sufficient length of time for the solution to take effect. The cover then is removed and the wound tress wet with a neutralizing solution, e. g. an oxidizing solution. After this, the quill is turned a short distance in a direction reverse to the winding direction and a second application of the neutralizing solution made.

Then the plug 80 of the element 76 (Fig. 4) is introduced into the free end 74 of the quill and the disc is forced up along the quill towards the plug spreading slightly as it does due to the flare of the quill, until the disc finally leaves the free end of the quill and frictionally engages the plug portion of said element. The position of the parts at this time is indicated in Fig. 5 from which it will be seen that this action results in disengaging the quill. Next the disc and wound strand are set back against the scalp. This manner of disengaging the quill results in flattening the wound strand between the bar 78 and disc 54 so that as the neutralizing solution takes effect it will cause the wound tress to be permanently waved in ringlet form.

It will be observed that the unit at this time simply consists of the disc and element 76, both of these being quite close to the scalp and both being of a soft flexible material so that not only is it convenient to walk around with these waving units on the head, but the patron also is able to sleep without too much discomfort while such waving units are in place.

It may be pointed out that the quill can be disengaged from the waving unit as above described either before the wound tress has been wetted with a neutralizing solution or thereafter and before the neutralizing solution has completed its task. Also, if desired, and either before or after the neutralizing solution is applied, the tress may be rinsed with clean lukewarm water as by spraying or pouring over the wound tress.

I have found that the setting, i. e. neutralizing solution, is not instantaneous in its action and therefore if, after such a solution is applied to the wound tress, said tress is flattened against the disc as above set forth and the flattened tress left in this condition for a period of time, say 15 minutes to one-half hour, or even longer, while the tress dries, the tress will be permanently waved either in ringlet form or in a form approaching ringlet form. The longer the tress is left in the condition indicated in Fig. 6 the closer the permanently waved tress will assume a ringlet form. Moreover, by permitting the tress to dry in a ringlet form it will be set in such form thereby eliminating the step of setting the hair in ringlets subsequent to permanent waving.

In lieu of employing an element 76 such as described, a metal element 90 (Fig. 7) may be used, said element consisting of a strip of spring steel or other resilient metallic material bent to form an elongated portion 92 with return bends 94 at its opposite ends extending into legs 96 which terminate in parallel arms 98 running at 90° to the elongated portion 92. The arms have flared tips 100 which are designed to frictionally engage the exterior of the hollow

free end 74 of a quill 52. The element 90 operates in the same manner as the element 76. When using the element 90 no flare need be provided on the quill, and the tips 100 will engage the underside of the disc to better hold the disc and element together.

Although it is proposed to sell all of the component elements of the hair waving unit as a combination, it is to be understood that individual component elements can be sold as replacement parts for use with other component elements of the unit.

It thus will be seen that I have provided an apparatus which achieves the several objects of my invention and meets the condition of practical use.

As various possible embodiments might be made of the above invention, and as various changes might be made in the embodiment above set forth, it is to be understood that all matter herein described, or shown in the accompanying drawings, it to be interpreted as illustrative and not in a limiting sense.

Having thus described my invention, I claim as new and desire to secure by Letters Patent:

1. A waving unit comprising in combination an elongated quill and a flexible disc, said disc having a through opening, said quill being frictionally received in said opening so as to be rotatable with respect to the disc about the longitudinal axis of the quill against the frictional restraint of the walls of the opening against the quill, said disc having a through slit to receive a tress of hair wound helically along the length of the quill from the distal to the proximal end of the tress and from the free end of the quill to the end of the quill at the disc, said slit extending from adjacent said opening to the periphery of the disc, and a projection extending away from the periphery of the disc adjacent the slit.

2. A waving unit comprising in combination an elongated quill and a flexible disc, said disc having a through opening, said quill being frictionally received in said opening so as to be rotatable with respect to the disc about the longitudinal axis of the quill against the frictional restraint of the walls of the opening against the quill, said disc having a through slit to receive a tress of hair wound helically along the length of the quill from the distal to the proximal end of the tress and from the free end of the quill to the end of the quill at the disc, said slit extending from adjacent said opening to the periphery of the disc, one edge of said slit being shaped in the form of a locking tab and the other edge in the shape of a mating recess whereby the portions of said disc on opposite sides of said slit may be detachably secured to one another.

3. A waving unit comprising in combination an elongated quill and a flexible resilient disc, said disc having a through opening, said quill being frictionally received in said opening so as to be rotatable with respect to the disc about the longitudinal axis of the quill against the frictional restraint of the walls of the opening against the quill, said disc having a through slit to receive a tress of hair wound helically along the length of the quill from the distal to the proximal end of the tress and from the free end of the quill to the end of the quill at the disc, said slit extending from adjacent said opening to the periphery of the disc, said disc having at least one through aperture adjacent said opening

whereby to enable said opening to frictionally receive quills of varying diameter.

4. For use in conjunction with a quill having an end thereof rotatably received in an opening in a disc, said quill being adapted to have wound thereon from its free end to its end adjacent the disc, a helical tress of hair: an element having an elongated portion and a portion normal thereto and intermediate the ends of the elongated portion, said last named portion being constructed to frictionally engage the quill adjacent the end opposite from the disc, and said elongated portion being adapted to flatten and press the flattened wound tress against the disc.

5. An element as set forth in claim 4 wherein the second-named portion is provided with a pair of spaced legs to engage the exterior of the free end of the quill.

6. An element as set forth in claim 4 for the use in conjunction with a quill having a hollow free end, the second named portion of said element being constructed to frictionally engage the interior of the hollow end of the quill.

7. In combination, a waving unit comprising an elongated quill and a flexible disc, said disc having a through opening, said quill being frictionally received in said opening so as to be rotatable with respect to the disc about the longitudinal axis of the quill against the frictional restraint of the walls of the opening against the quill, said quill having its free end hollow, said disc having a through slit to receive a tress of hair wound helically along the length of the quill from the distal to the proximal end of the tress and from the free end of the quill to the end of the quill at the disc, said slit extending from adjacent said opening to the periphery of the disc, and an element having an elongated portion and means intermediate the ends of said elongated portion for frictionally engaging said hollow end of the quill.

8. In combination, a waving unit comprising an elongated quill and a flexible disc, said disc having a through opening, said quill being frictionally received in said opening so as to be rotatable with respect to the disc about the longitudinal axis of the quill against the frictional restraint of the walls of the opening against the quill, said disc having a through slit to receive a tress of hair wound helically along the length of the quill from the distal to the proximal end of the tress and from the free end of the quill to the end of the quill at the disc, said slit extending from adjacent said opening to the periphery of the disc, said quill of about the same diameter from the free end thereof to the disc to enable the disc to be slid along and off the quill, and an element having an elongated portion and a portion detachably engaging the free end of the quill and engageable in the opening of the disc, whereby said disc may be slid along the quill until it engages the second named portion of said element and thereafter said quill may be freed from said disc and the wound tress held flattened between said element and said disc.

9. For use in conjunction with a waving unit comprising in combination an elongated quill and a flexible disc, said disc having a through opening, said quill being frictionally received in said opening so as to be rotatable with respect to the disc about the longitudinal axis of the quill against the frictional restraint of the walls of the opening against the quill, said disc having a through slit to receive a tress of hair wound

helically along the length of the quill from the distal to the proximal end of the tress and from the free end of the quill to the end of the quill at the disc: an element having an elongated portion and a portion detachably engaging the free end of the quill and engageable in the opening of the disc whereby said disc may be slid along the quill until it engages the second named portion of said element and thereafter said quill may be freed from said disc and the wound tress held 10 flattened between said element and said disc.

10. An element as set forth in claim 9 for use with a quill having a hollow free end, the second named portion of said element comprising a member perpendicular to the first named portion and frictionally receivable in the hollow end of the quill.

11. A thin flexible disc for use in permanently waving hair on the human head, said disc having a through circular aperture and a through slit 20 which extends from adjacent said aperture to the periphery of the disc, and a projection integral with and extending radially away from the periphery of the disc adjacent the slit.

12. A thin flexible disc for use in permanently waving hair on the human head, said disc having a through circular aperture and a through slit which extends from adjacent said aperture to the periphery of the disc, one edge of the slit being shaped in the form of a locking tab with a constricted base and the other edge in the shape of a mating recess whereby the portions of said disc on opposite sides of said slit may be detachably secured to one another.

JOSEPH S. CIPOLLA.
